J. H. Gibbs

ATTORNEY.

UNITED STATES PATENT OFFICE.

ALLEN E. OSTRANDER, OF RIDGEWOOD, NEW JERSEY, AND HERBERT H. WILLIAMS, OF BROOKLYN, NEW YORK, ASSIGNEES OF ONE-HALF TO AMERICAN CAR AND FOUNDRY COMPANY, OF NEW YORK, N. Y., A CORPORATION OF NEW JERSEY, AND ONE-HALF TO METROPOLITAN ENGINEERING COMPANY, OF BROOKLYN, NEW YORK, A CORPORATION OF NEW YORK.

JOURNAL BOX.

1,415,109.

Specification of Letters Patent. Patented May 9, 1922.

Application filed March 23, 1921. Serial No. 454,763.

To all whom it may concern:

Be it known that we, ALLEN E. OSTRANDER and HERBERT H. WILLIAMS, residing at Ridgewood, county of Bergen and State of New Jersey, and Brooklyn, county of Kings, and State of New York, respectively, and being citizens of the United States, have invented certain new and useful Improvements in a Journal Box, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Figure 1 is a central vertical section of our improved journal box;

25 Figure 2 is partly a top plan view and partly a horizontal section on the line 2—2 of Fig. 3;

30 Figure 3 is partly a rear elevation and partly a vertical section on the line 3—3 of Fig. 2;

Figure 4 is a vertical section on the line 4—4 of Fig. 2;

35 Figure 5 is a front elevation of the reinforcing member; and

Figure 6 is a section on the line 6—6 of Fig. 1.

It is the object of our invention to provide an improved pressed metal journal box that shall be of great strength and durability and 40 can be manufactured at comparatively small cost.

In the embodiment of our invention shown in the drawings, the box comprises a pressed metal cellar 1, a pressed metal top 2 having two of its edges bent downwardly and butt welded, as at 3, to the sides 4 of the cellar 1. The box is provided with corrugations 5 extending from the top to the bottom of the sides of the box and of greater width at the bottom than at the top of the box. To the bottom 6 of the cellar 1 welds 7 secure a yoke 8 provided with openings adapted to

receive the journal box bolts and having a recess adapted to receive the cellar 1 and portions 9 adapted to engage in the corrugations 5 so that stresses may be transmitted from one to the other without danger of rupturing the welds 7.

To reinforce the top 2 there is provided an inner reinforcing member 10 having downwardly extending projections 11 that fit the corrugations 5 and are adapted to serve as stops for the journal brass. The member 10 is also provided with the downwardly extending projections 12 adapted to serve as stops for the journal box wedge. There is also provided an outer reinforcing member 13 that serves as a yoke and is provided with openings adapted to receive the journal box bolts. To secure the yoke 13 and reinforcing member 10 to the box top 2 the yoke 13 is provided with a plurality of cylindrical projections 14, of a length slightly greater than the thickness of the box top 2, which are passed through openings in the box top 2 and engaged with the member 10. An electric current of an amperage sufficient to heat the projections 14 is then passed between the members 10 and 13 and when the projections 14 are heated to a welding temperature the members 10 and 13 are subjected to pressure thus effecting a plurality of welds that firmly unite the members 10 and 13 together and to the box top 2.

The dust guard pocket comprises a sheet 15 provided with an opening to receive the axle, the metal surrounding the opening being bent outwardly and backwardly forming an annular groove adapted to receive the inwardly bent rear edge of the box top 2 and the edge of the corresponding opening formed in the rear wall 16 of the cellar 1. The sheet 15 is flanged on three sides, as at 17, and the flanged sheet 15 is slipped into a sheet 18 correspondingly flanged, as at 19, and having an axle opening therein, after which the flanges 19 are bent down over the flanges 17 so as to secure the sheets 15 and 18 together. The dust guard is then slipped into the opening formed in the rear wall 16 of the cellar 1 and is held in place by engagement with the top 2 when the top 2 is welded to the cellar 1.

The top 2 is provided with a hinge lug 20

that may be formed integral with the top 2 or be formed separately and be secured to the top 2 by welding as on the line 21.

What we claim is:

- 5 1. A journal box comprising top and cellar sections, inner and outer reenforcing members secured to said top section and a dust guard pocket secured to said box by uniting said top and cellar sections.
- 10 2. A journal box comprising top and cellar sections, a reenforcing member and a yoke secured to said top section and a yoke secured to said cellar section and recessed to receive said section.
- 15 3. A journal box comprising top and cellar sections and a dust guard pocket attached to said box by having a member interlocked with said top and cellar sections and a second dust guard pocket member interlocked 20 with said first member.
- 25 4. A journal box comprising top and cellar sections, a dust guard pocket member secured to said box by uniting said top and cellar sections and a second dust guard pocket member interlocked with said first member.
- 30 5. A journal box comprising a cellar section having corrugations in its sides, a top section welded to said cellar section, a yoke carried by said top section and an inner reenforcing member for said top section welded to said yoke and having means engaging

said corrugations and serving as a stop for the journal brass.

6. A journal box comprising a top section 35 and a cellar section welded thereto and having corrugations in its sides, a yoke secured to said top section and adapted to reenforce said top section, a second yoke secured to said cellar section and recessed to receive 40 said cellar section and means on said second yoke to engage said corrugations.

7. A journal box comprising top and cellar sections welded together and inner and outer reenforcing members for said top section welded together so as to be secured to said top, said inner reenforcing member having means adapted to serve as stops for the journal brass and wedge.

8. A journal box comprising top and cellar sections, a yoke secured to said cellar section and interlocking therewith, a reenforcing yoke secured to said top section and an inner reenforcing member secured to said reenforcing yoke and having stops for the 55 journal brass.

In witness whereof we have hereunto set our hands in the presence of two witnesses.

ALLEN E. OSTRANDER.
HERBERT H. WILLIAMS.
